SINGLE-SHUTTLE TWIN-BARREL GUN

Samuel Altschuler, Skokie, Ill., assignor, by mesne assignments, to the United States of America as represented by the Secretary of the Army

Filed Feb. 8, 1957, Ser. No. 639,142

4 Claims. (Cl. 89—33)

My invention relates to automatic guns having twin barrels and more particularly to such guns having corresponding feed sprockets and shuttles for successive cooperation therewith to secure cartridges for alternate discharge in firing stations in respective axial alignment with the barrels.

This application is submitted for copending consideration with the application of Charles R. Bell and Eugene S. Wassel entitled "Ammunition Belt for Shuttle Gun," Serial No. 680,371, filed August 26, 1957.

Conventional automatic guns include receivers with considerable structure projecting rearwardly from the firing station of the cartridges, and it is an object of my invention to provide an automatic gun with twin barrels, laterally spaced in a receiver, and anvils with firing pins disposed substantially at the rear end of the receiver to minimize the length thereof.

Another object of my invention is to provide such a gun which fires cartridge alternately through the barrels.

A further object of my invention is to provide such a gun with a feed device including sprockets corresponding to the barrels for conveying the cartridges to the firing stations in respective axial alignment with the barrels.

A still further object of my invention is to provide the gun with a device including a shuttle which cooperates alternately with the sprockets to secure the cartridges in the firing stations for the discharge.

Still another object of my invention is to provide such a gun which fires noncylindrical cartridges.

An additional object of my invention is to provide such a gun with a device including a discharge gas cylinder and a piston for rotating the sprockets, responsive to discharge of the gun.

Other aims and objects of my invention will appear from the following description.

In carrying out my invention, a feeder includes cylindrical sprockets corresponding to the barrels and disposed on fixed axles for alternately feeding noncylindrical cartridges from a pair of ammunition belts to firing stations in axial alignment with the barrels and in position for discharging the cartridge projectile therethrough. A rotationally stabilized hollow piston is spring-biased to a normal position and disposed for longitudinal reciprocation responsive to gases from the discharge.

The piston is secured to members having radially slidable pins with each member being provided with a mechanism connecting the pins with internal cam tracks in the sprockets for rotation thereof responsive to the piston strokes.

The gun is provided with a device including a shuttle transversely slidable in the receiver and a crank provided with an axially journaled shaft and an axle offset therefrom. A projection of the shaft is disposed within the piston and provided with cam grooves engageable with internal rollers of the piston for rotating the crank responsive to the piston strokes. The axle engages an aperture through the shuttle to provide reciprocation thereof from and to firing station engagement with the respec-

2

tive sprockets responsive to the rotation. The shuttle and the sprockets are disposed to secure the cartridges in the firing stations for the discharge.

For a more complete understanding, reference is directed to the following description and the accompanying drawings in which:

Fig. 1 is a plan view, partly in section, of a gun incorporating my invention;

Fig. 2 is a view along line 2—2 of Fig. 1;

Fig. 3 is a view along line 3—3 of Fig. 1;

Fig. 4 is a partial view similar to Fig. 3 with the shuttle in an intermediate position;

Fig. 5 is a view along line 5—5 of Fig. 3 with shaft and tines removed; and

Fig. 6 is an isometric view, partly in section, of the piston, the cartridge indexing mechanism, and the mechanical convertor.

Shown in the figures is a gun 12 provided with a receiver 14, and a pair of barrels 16 and 18 which are laterally spaced therein. Cartridges 30 are linked to form a pair of ammunition belts 28 and are fed to firing stations respective to the barrels 16 and 18 by a cartridge indexing mechanism provided with a feeder. Such feeder includes a pair of cylindrical sprockets 20 which are rotatably mounted, by means of axial bores 21 therethrough, on a pair of shafts 23 which are integrally fixed in opposite sides of receiver 14. Each of the sprockets 20 is provided with a plurality of teeth 24 which engageably carry the cartridges 30 therebetween to the firing stations

20 of the respective ones of the barrels 16 and 18 and in engagement with respective ones of a pair of anvils 31 which are positioned in the rear end of receiver 14 in axial alignment with the barrels. The anvils 31 are the sole components of gun 12 disposed rearwardly of the

25 firing station to minimize the length of the gun, and each of the anvils is provided with a firing pin 33 which is adapted to fire the cartridge 30 engaged therewith by conventional electrical means.

Each one of the cartridges 30 includes a case 32, which 40 is substantially quadrangular in cross-section and which is provided with a side 34 having a concave surface which coincides with the perimeter of the sprockets 20 between the teeth 24, a pair of sloping sides 38, and a side 36 which joins sides 38 opposite side 34. Provided at the

45 junctions of side 34 with the sides 38 and disposed centrally thereof are interlocking means 39, such as disclosed by Bell and Wassel in their aforementioned application, which cooperate in linking the cartridges 30 together to form the belts 28 and are received by corresponding

50 grooves 40 through the teeth 24, as shown in Fig. 4. A cylinder 42 is provided in receiver 14 between the barrels 16 and 18 and slidably receives a piston 44 having an annular flange 45 slidably engageable with such cylinder. The barrels 16 and 18 communicate respectively with cylinder 42 through ducts 46 and 47 which open respectively into the rear and front ends of the cylinder to discharge gases from the barrels against the rear and front sides of flange 45 to drive piston 44 forwardly and rearwardly when the barrels are alternately discharged.

60 The sprockets 20 are rotated to feed the cartridges 30 to the firing stations by a pair of mechanical converters 48 which are connected by yoke 52 to a piston 44 which is disposed therebetween, whereby the converters are

65 slidably actuated together in receiver 14 responsive to the operation of the piston, and the piston is fixed against rotation by such converters. The shafts 23 are of I-cross-section with the principal axis of the web portion being disposed transversely to the gun, and the outer surfaces of the flange portion are arcuately formed to provide bearing supports for the sprockets 20 rotatably mounted thereon, as best shown by Figs. 2 and 3. Each of the converters 48 is provided with a pair of longitudinally-

disposed rods 54 which are fixed at the front ends to yoke 52 and are vertically spaced to be received by the corresponding spaces between the flange portions of the shafts 23 and thereby permit the sliding movement of such members along such shafts.

Each of the rods 54 is terminated at the rear end by a flange 55 which is slidably received by respective ones of the spaces in the shaft 23 with the outside of each of the flanges being arcuately formed to slidably engage bore 21 of the respective sprocket 20.

Arranged symmetrically in each of the flanges 55 is a pair of radially-disposed bores 57, the axes of which form a 60° angle. A pin 56 is slidably received by each of the bores 57 so that a roller 58 mounted to the outer end of each of the pins 56 is actuatable between positions of retraction within and extension from the flange 55. A gear rack 64 is provided on each of the pins 56, as shown in Fig. 3, and a pinion gear 66 rotatably mounted on a shaft 68 jointly engages said gear racks whereby one of said rollers is positioned in the extension position and the other in the retraction position and whereby movement of the roller from the extension to the retraction position moves the other one of the rollers from the retraction to the extension position.

Provided in each of the bores 21 are three U-shaped cam tracks 60, as illustrated in Fig. 5, which slidably receive the rollers 58 in the extension positions for rotating the sprockets 20 as hereinafter described. The leg portions of the cam track 60 are longitudinally disposed in the bores 21 and spaced 60° apart, and corresponding ones of the leg portions of each of the cam tracks 60 is terminated by a ramp portion 62 which cammingly moves the rollers 58 in the extension positions to the retraction positions after completing the travel thereof along the cooperating one of the cam tracks. As the leg portions of the cam tracks 60 are spaced 60° apart and as the rollers 58 in each of the flanges 55 are also spaced 60° apart, when the rollers in the extension position are cammed into the retraction positions, the other rollers are slidably received by the beginning portions of the succeeding cam tracks, as best shown in Fig. 3, whereby the sprockets 20 are rotated another pitch of 60° during the following reciprocation of piston 44.

Each of the gears 66 is provided with a toggle including an arm 70 secured to respective shafts 68, and each arm is engaged by a flat spring 71 secured to the respective flange 55 to stabilize the movement of the pins 56.

A shuttle 72 provided with opposing apertures 74 is laterally slidable in receiver 14 between positions for alternate cooperation with sprockets 20 to retain cartridges 30 in the firing stations for the discharge.

A conversion device for reciprocation of shuttle 72 responsive to the axial stroke operation of piston 44 includes a crank 76 with a pair of disks 78 transversely rotatable in receiver 14, a shaft 80 projecting into piston 44, and an axle 82 projecting through axial hole 84 in shuttle 72. The axes of shaft 80 and axle 82 are spaced at a throw distance, and shaft 80 is provided with a pair of cam grooves 87 for engagement with opposed rollers 88 projecting internally from piston 44, as shown in Fig. 1. Grooves 87 are disposed for 180° oscillation of crank 76 for reciprocation of shuttle 72 between the engagements thereof with the opposite ones of the sprockets 20 responsive to the stroke operation of piston 44.

Apertures 74 of shuttle 72 are disposed for engagement with side 36 and the plane portions of sides 38 to retain cartridges 30 against sprocket 22 in the firing stations for discharge, and the surfaces of the plane portions of sides 38 of the cartridges diverge from opposite sides 36 to facilitate the engagement.

Axle 82 is ovoid in cross-section and hole 84 is shaped to constantly engage shuttle 72 to axle 82 during the reciprocation.

Cam tracks 60 are disposed for respective rotation of

the free sprocket and the sprocket in engagement with shuttle 72 responsive to beginning and end portions of the piston strokes, and grooves 87 are disposed for displacement of shuttle 72 between the engagement positions responsive to the remainder of the piston strokes.

Crank 76 is axially fixed in receiver 14 and provided with a stud 98 axially projecting into piston 44. Stud 98 includes a pair of spaced shoulders 100, and a spring 102 surrounds stud 98. A pair of washers 104 are respectively disposed between spring 102 and shoulders 100, and a tube 106 mounted axially to piston 44 at the front end thereof incloses the spring and washers. Tube 106 includes a pair of internal flanges 108 for engagement with washers 104 to bias piston 44 to a normal position whereby flange 45 is disposed forwardly of duct 46 for the forward operation of the piston responsive to gases from the discharge of a cartridge 30 through barrel 16 to begin the cycle of operation of gun 12.

Thus, to ready gun 12 for firing, a cartridge belt 28 is engaged with each of the sprockets 20 and moved thereby through suitable manual charging means (not shown) until the leading one of the cartridges 30 in the belt feeding barrel 16 is in the feeding station thereof and chambered through the cooperation of such sprocket, 25 shuttle 72 and the respective one of the anvils 31. As piston 44 is normally biased to the normal position in cylinder 42 by spring 102 and as the bore of barrel 16 communicates with the rear end of the cylinder by duct 46, such barrel is to be fired first whereby the gases from the discharge of the cartridge 30 by the respective one of the firing pins 33 enter such cylinder rearwardly of flange 45 which forces piston 44 to the forward position. During such forward movement, sprockets 20 are rotated through the cooperation of rollers 58 with the cam grooves 35 60 to deliver a cartridge 30 to the firing station of barrel 18 and move the fired cartridge case 32 from the firing station of barrel 16. At the same time, crank 76 is rotated 180° to move shuttle 72 into engagement with the cartridge 30 in the firing station of barrel 18 to cooperate in the chambering thereof. When such cartridge is ignited by the engaged firing pin 31, the lateral force of the discharge of cartridge 30 is taken by the supporting shaft 23, which is of I-cross-section, with the principal axis thereof being laterally disposed to oppose the force of the discharge. The gases from the discharge are vented through duct 47 to the front end of cylinder 42 to move piston 44 rearwardly and thereby rotate the sprockets 20 and move shuttle 72 to repeat the aforementioned sequences of operation.

Although a particular embodiment of the invention has been described in detail herein, it is evident that many variations may be devised within the spirit and scope thereof and the following claims are intended to include such variations.

55 I claim:

1. In a gun having a receiver, a pair of barrels spaced laterally in the receiver, a piston slidably mounted in a cylinder, duct means providing communication between said barrels and said cylinder to reciprocably actuate said piston when said barrels are alternately discharged, a pair of anvils mounted to the rear end of the receiver in axial alignment with respective ones of said barrels and in spaced relationships with the breech ends thereof to receive a cartridge therebetween at a firing station respective to each of said barrels, a firing pin mounted to each one of said anvils for discharging the cartridge when in the respective one of the firing stations, a pair of sprockets rotatably mounted to the receiver for feeding said cartridges linked to form a pair of belts to respective ones of said firing stations, a shuttle mounted for lateral movement in the receiver to cooperate with alternate ones of said anvils and said sprockets for chambering said cartridges for discharge when in said firing stations, and piston-actuated cam means for simultaneously actuating said sprockets and said shuttle to feed said cartridges to

alternate ones of said firing stations and chamber said cartridges therein.

2. The gun as described in claim 1 including a crank engaged with said shuttle for movement thereof into alternate engagement with said sprockets, and cam means disposed between said crank and said piston for rotating said crank 180° to move said shuttle into engagement with the other one of said sprockets during actuation of said piston between the limits of movement thereof.

3. The gun as described in claim 1 wherein each of said sprockets are provided with teeth for engageably moving said belts to respective ones of said firing stations with said cartridges in said belts being received by the spaces between said teeth, and said shuttle is provided with apertures in the ends thereof which are sequentially engageable with alternate ones of said sprockets to cooperate with said spaces and said anvils in forming chambers for said cartridges respective to said barrels.

4. The gun as described in claim 1 wherein said cam means for converting the reciprocation of said piston to rotation of said sprockets includes a pair of flange portions

5 mounted for reciprocation in an axial bore provided in each of said sprockets, means for transferring reciprocation of said piston to said flanges, a plurality of U-shaped cam tracks symmetrically arranged in said bores, a pair of rollers mounted to each of said flange portions for reciprocation between positions of retraction within said flange and extension therefrom into cooperation with said cam tracks for rotating said sprockets one pitch during each reciprocation of said piston, ramp means engageable by said rollers in said extension positions when at the end of the travel thereof in each of said cam tracks for actuating said rollers to said retraction positions, and gear means for converting movement of said rollers to the retraction positions to movement of the other ones of said rollers to the projecting positions and into sliding engagement with the front ends of the succeeding ones of said cam tracks.
